CUTTING MECHANISM FOR WOOLEN SHEARS

Leland F. Remington, Worcester, Mass., assignor
to Curtis & Marble Machine Company, Worcester, Mass., a corporation of Massachusetts

Application January 17, 1942, Serial No. 427,127

6 Claims. (Cl. 26—15)

This invention relates to machines for shearing the face of a piece of woolen cloth or other similar fabric, as an important step in the cloth finishing process. In such machines, commonly termed "woolen shears," it is customary to draw the cloth over a fixed cloth rest or guide and to provide coacting fixed and revolving cutters, which cutters perform their cutting or trimming action along a fixed straight line, more or less closely adjacent to the fixed cloth rest. In the operation of such machines, various changes in relationship between the cutters and the cloth rest and also between the fixed and revolving cutters must be effected from time to time.

It is the general object of my invention to provide an improved construction by which these various changes in relationship may be conveniently accomplished and by which desired adjustments may be reliably restored or maintained.

My invention further relates to arrangements and combinations of parts which will be herein-after described and more particularly pointed out in the appended claims.

A preferred form of the invention is shown in the drawings, in which

Fig. 1 is a plan view of parts of a woolen shear embodying my improvements;

Fig. 2 is a partial side elevation, looking in the direction of the arrow 2 in Fig. 1;

Fig. 3 is a view similar to Fig. 2 but with certain parts omitted and with others shown in a different relationship;

Fig. 4 is a plan view, partly broken away, of a lower movable support on which the fixed cutter blade is mounted, together with certain associated parts;

Fig. 5 is an end elevation thereof, looking in the direction of the arrow 5 in Fig. 4; and

Fig. 6 is a partial rear elevation, looking in the direction of the arrow 6 in Fig. 4.

Referring to Figs. 1 and 2, I have shown a side portion of the fixed frame F of a woolen shear, which frame supports a guide or rest 10 for the cloth C. I have also shown a relatively fixed blade or cutter B and a rotating cutter or "revolver" R.

The cutter R is constructed on a bar having gudgeons 12 and may be rotated by a plurality of belts 14 acting on a pulley 15. The gudgeons 12 are rotatably supported in bearings 20 at each side of the machine, one of which is clearly shown in Figs. 1 to 3. Each bearing 20 is mounted on an arm 22 which is pivoted on a

shaft 24 which extends across the machine from one side to the other.

The fixed blade B is fastened along the edge of a blade-holding plate 25 (Fig. 3), which in turn is mounted on a lower movable base or support 30. The support 30 extends across the machine from one side to the other, as indicated in Fig. 4, and is mounted on a rock shaft 31, which in turn is supported at its ends on open-face bearing blocks 32 mounted on side portions of the frame F.

The blade holder plate 25 is secured in adjusted position on the movable support 30 by a plurality of clamping screws 33 and by a plurality of adjusting screws 34 and 35. By adjustment of the screws 34 and 35, the blade B may be raised or lowered relative to the support 30 or may be rocked relative thereto. The blade is held fast by the screws 33.

The shaft 24 for the cutter bearing arms 22 is mounted in bearing blocks 40 (Fig. 5) which are bolted to the rear of the movable support 30 and near the opposite ends thereof. Arms 42 extend rearward from the bearing blocks 40 and form, in effect, rearward extensions of the support 30.

A cross rod 43 (Fig. 4) connects the arms 42, and tension springs 44 (Figs. 2 and 3) are connected to the rod 43 and partially counterbalance the movable support 30 and the cutters and other parts associated therewith.

Adjustable stop screws 46 are threaded in forwardly-extending portions of the support 30 and may be held in adjusted position by lock nuts 47. The enlarged lower ends or heads 48 of the screws 46 rest on cams or eccentrics 50, mounted near each side of the machine on a cam shaft 51 rotatable in fixed bearings 52 (Fig. 2) at the front of the frame F. A worm wheel 54 (Figs. 1 and 2) is mounted near one end of the shaft 51 and is engaged by a worm 55 on a short shaft 56 provided with a hand wheel 57. By turning the hand wheel 57, the shaft 51 and the eccentrics 50 may be rotated, thus simultaneously and equally raising or lowering the spaced ends of the movable support 30.

The screws 46 may be separately adjusted for initial leveling of the support 30, after which the hand wheel 57 is used for adjusting the support 30, with its fixed and revolving cutters, relative to the fixed cloth rest or guide 10. A graduated dial 58 and a fixed index 59 may be provided at one end of the shaft 51, to indicate the amount of adjustment. The dial 58 may be calibrated to show the extent of clearance be-

tween the cloth rest 10 and the non-rotating blade B.

In the operation of a woolen shear, it is customary to stitch the ends of successive pieces of cloth together, so that the operation of the machine may be continuous, and it is necessary for the operator to raise the cutters away from the cloth rest to clear the seams as they appear at the shearing point. For this purpose, links 60 are pivoted at 61 to the forward ends of the movable support 30 and are connected at their lower ends to lifting devices including arms on a cross shaft and manual lifting levers by which the cutters may be quickly shifted out of operative position as a seam approaches. This mechanism for manually raising the links 60 is of a usual commercial construction and, as it forms no part of the present invention, it is not shown in detail herein.

It has been previously stated that the rotating cutter or revolver R and its shaft 12 are supported in bearings on the arms 22, which arms in turn are pivotally supported on the cross shaft 24 mounted at the rear of the movable support 30. An adjusting screw 70 (Fig. 3) is provided at the front end of each arm 22, with the enlarged lower end or head 71 thereof engaging an upper surface of the support 30. By adjusting the screws 71, the desired clearance between the rotating cutter R and the non-rotating blade B may be conveniently established. The adjustment may be retained by lock nuts 72. A graduated dial 73 and index 74 enable the operator to readily determine the amount of adjustment.

In the operation of a woolen shear, it becomes necessary at intervals to substantially separate the blade B from the cloth rest 10, and furthermore to substantially separate the revolving cutter R from the non-rotating blade B, so that a sharpening or honing operation may be conveniently performed.

It has been the usual practice to entirely remove the rotating cutter or revolver R from the machine in order to perform this honing operation, and such removal and replacement of the rotating cutter has involved very considerable time and expense.

In my improved machine, I provide special mechanism by which the fixed and rotating cutters may be spaced from the fixed cloth rest and also from each other for a honing operation by the simple turning of a hand wheel and without any substantial delay.

In order to accomplish this result, I provide a link 80 at each side of the machine, said links being pivoted at 81 to the forward ends of the arms 22. The lower ends of the links 80 are slotted at 80^a to receive studs 82 in arms 83 fixed to a cross shaft 84. The shaft 84 is rotatable in fixed bearings (not shown) and is provided with a worm wheel 85 engaged by a worm 86 mounted on a short vertical shaft 87 and provided with a hand wheel 88.

By rotating the hand wheel 88, the arms 83 may be swung upward in the direction of the arrow a in Fig. 2, thus lifting the links 80 which are connected to the revolver supporting arms 22. The front ends of these arms are thus raised.

It has been pointed out, however, that the arms 22 are pivoted on the shaft 24, which shaft is mounted on the lower support 30 at a point substantially rearward of the shaft 31 by which the support 30 is pivotally sustained. Consequently, as soon as the links 80 begin to lift the arms 22 and associated parts, the weight of these parts is

removed from the adjusting screws 71 which rest on front portions of the support 30, while at the same time a substantial part of the weight of said elements is applied to the support 30 at the axis 5 of the shaft 24 and rearward of its pivot shaft 31.

The application of this weight, which coacts with the tension of the counterbalance springs 44, causes the support 30 to swing upward as indicated in Fig. 3, until the arms 42 engage fixed 10 stop screws 90 (Figs. 2 and 3). Such movement of the support 30 causes the blade B to clear the cloth rest 10, as indicated in Fig. 3, being thus placed in suitable honing position.

After the support 30 and blade B reach the position shown in Fig. 3, continued operation of the hand wheel 88 and the links 80 swings the arms 22 about the axis of the shaft 24, thus lifting the cutter R from the blade B, also as indicated in Fig. 3.

It accordingly appears that by simple use of the hand wheel 88, the cutters B and R may be spaced from the fixed cloth rest and also from each other, so that sharpening or honing may be conveniently performed. By reverse movement of the hand wheel 88, the parts are as quickly and easily restored to operative position and without loss of previous adjustment.

The slots 80^a in the lower ends of the links 80 are provided so that the reverse movement of the arms 83 may be continued until the studs 82 have substantially cleared the upper ends of the slots. The slots also permit lifting of the cutters by the manual lifting levers to clear the seams.

From the foregoing description, it will be evident that I have provided very convenient mechanism for quickly and easily performing all necessary adjustments of the fixed and rotating cutters relative to each other or to the fixed cloth rest. I also provide for convenient movement of these parts to suitable positions for shearing, seam-clearing or honing.

Having thus described my invention and the advantages thereof, I do not wish to be limited to the details herein disclosed, otherwise than as set forth in the claims, but what I claim is:

1. In a cloth shear, a fixed frame, a cloth rest fixed in said frame, a lower cutter support pivoted on said fixed frame, a non-rotated blade mounted on said support and operatively positioned thereby adjacent said cloth rest, a revolving cutter coacting with said blade, and bearing arms on which said revolving cutter is mounted, said bearing arms being pivoted on said lower cutter support at points rearward of the pivot of said support on said fixed frame.

2. The combination in a cloth shear as set forth in claim 1, in which elevating means is provided which is effective to first raise said blade and cutter as a unit from said cloth rest and to thereafter raise said cutter from said blade.

3. The combination in a cloth shear as set forth in claim 1, in which elevating means is provided which is effective to first raise said blade and cutter as a unit from said cloth rest and to thereafter raise said cutter from said blade, all by application of continuous lifting forces to said cutter bearing arms only.

4. The combination in a cloth shear as set forth in claim 1, in which a separate adjustable stop is provided for each bearing arm, said stops engaging said lower support and being jointly effective to determine the operative position of the revolving cutter relative to the non-rotated blade.

5. The combination in a cloth shear as set forth in claim 1, in which vertical adjusting de-

vices are provided on the lower cutter support, said devices engaging spaced eccentric members on a cross shaft pivoted on said fixed frame, and means being provided to turn said shaft and to thereby simultaneously and equally change the elevation of both ends of said lower support.

6. The combination in a cloth shear as set forth in claim 1, in which vertical adjusting devices are

provided on the lower cutter support, said devices engaging spaced eccentric members on a cross shaft pivoted on said fixed frame, and a worm wheel, worm and hand wheel being provided to turn said shaft and to thereby change the elevation of said support.

LELAND F. REMINGTON.
